OIL COOLER

Oscar C. Palmer, Phoenix, Ariz.

Application September 13, 1932, Serial No. 632,945

4 Claims. (Cl. 257—125)

This invention relates to internal combustion engines and more particularly to the lubrication systems of engines of this general classification.

An object of the present invention is to provide improved and simplified means for controlling the temperature of the lubricating oil of an internal combustion engine.

A more detailed object is to provide an oil temperature regulator for an internal combustion engine, which includes a cooling unit through which the oil is circulated, wherein the cooling unit is cooperatively associated with the radiator which forms a portion of the cooling system of the engine. This cooperative relationship between the oil cooling unit and the radiator is brought about by embodying the unit in an attachment which can quickly and easily be connected to the radiator and/or to one of the conduits whereby the water is fed to or from the radiator.

A further object of my invention is to provide an oil cooler having the general characteristics described, which is of simple, rugged and economical construction, which is capable of operating with a high degree of efficiency in cooling the lubricating oil of the engine with which it is associated, and which is not liable to interfere with the normal operation of either the cooling system or the lubricating system of the engine.

The invention comprises other objects and valuable features, some of which, with the foregoing, will be set forth in the following description of the preferred form of my invention. It is to be understood that I do not limit myself to the specific disclosure made by said description, as I may adopt variations of the preferred form within the scope of my invention as set forth in the claims.

Referring to drawing:

Figure 1 is a longitudinal, vertical sectional view of the lower portion of a radiator and the coupling whereby the lower hose is attached thereto and showing a cooling unit embodying the principles of the present invention operatively associated therewith.

Figure 2 is a transverse, vertical sectional view, the plane of section being indicated by the line 2—2 of Figure 1 and the direction of view by the arrows.

In terms of broad inclusion, the present invention contemplates the provision of a device for cooling the oil used in lubricating an internal combustion engine. This device comprises a cooling unit so interconnected with the lubricating system of the engine that the oil thereof is

caused to flow through the unit; and the unit is so interposed into the cooling system of the motor that heat is extracted from the oil by the water or other cooling medium employed in the cooling system. The oil cooling unit is so arranged that it is closely associated with the radiator, preferably being embodied as an attachment releasably mounted either in the radiator itself or in one of the conduits which establish communication between the radiator and the water jacket of the engine.

Figures 1 and 2 illustrate a preferred embodiment of my oil cooling unit in the form of a fitting which is releasably secured to a radiator 106 in such position that the water flowing from the radiator 106 to the lower hose 107 is caused to impinge against a plurality of tubes through which the lubricating oil used to lubricate an internal combustion engine (not shown) is caused to flow. This unit which is indicated in its entirety at 108 is constructed similarly to a small section of conventional radiator core, being composed of a plurality of tube members 109 disposed in spaced parallel relationship and each of these members being composed of a pair of opposed plates having aligned beads extending longitudinally thereof to define tubes or oil passages 111. These passages communicate at their ends with upper and lower header tanks 112 and 113 respectively. The tube members 109 are separated by cooling fins 114 which preferably are corrugated and which assist materially in conducting heat from the oil flowing through the tubes 111 and disseminating it to the water flowing through the spaces 116 between the tube members 109. The spaces 116, or water passages, communicate at one end 117 of the unit 108 with the interior of the lower header tank 118 of the radiator 106; and to the other end 119 of the unit 108 a mounting flange 121 is soldered or otherwise secured. Through this flange 121 preferably a plurality of openings 122 communicating with the water passages 116 extend. The unit 108 is of small enough cross-sectional area to permit it to be inserted into the header tank 118 through the port 123 which is conventionally provided in the after wall 124 thereof in order to establish communication between the lower hose and the lower header tank. This hose 126 is fastened to the radiator 106 by means of a tubular fitting 127 having a flange 128 secured against the after wall 124 as by cap screws 129 so as to hold its bore 131 in registry with the port 123 in the wall 124. However, the flange 121 preferably corresponds in size to the flange 128 of the

fitting 127 and is interposed between the flange 128 and the wall 124 of the tank 118 so as to mount the unit 108 rigidly in operative position. Oil is supplied to preferably the upper header tank 112 of the unit 108 by a tube 136 leading from the lubricating system of the associated engine. Preferably the tube 136 extends through the side wall of the fitting 127 into the bore 131 thereof and thence through the flange 121 into the upper header tank 112 of the oil cooling unit 108. Oil is conducted from the unit 108 by a tube 137 which is similar to the tube 136 except that it communicates with the lower header tank 113.

As a slightly different form of this same modification it should be understood that the unit 108 might be disposed within the bore 131 of the fitting 127 instead of extending into the header tank 118 of the radiator 106. This modification is so similar to that illustrated upon Figures 1 and 2 that it has not been deemed necessary to illustrate it further.

I claim:

1. An oil temperature regulating device for an internal combustion engine having a lubricating system and a cooling system including a radiator having a header tank having a port in a wall thereof, a tubular coupling secured to said tank with its bore communicating with said port, and a conduit secured to said coupling and leading to said engine, said regulating device comprising a flange interposed between said coupling and said header tank, means carried by said flange providing a plurality of oil passages and a plurality of water passages extending adjacent to said oil passages, said water passages extending through said flange to establish communication between said bore and said header tank, and means interconnecting said oil passages with said lubricating system whereby the lubricant thereof is circulated through said oil passages.

2. An oil temperature regulating device for an internal combustion engine having a lubricating system and a cooling system including a radiator having a header tank having a port in a wall thereof, a tubular coupling secured to said tank

with its bore communicating with said port, and a conduit secured to said coupling and leading to said engine, said regulating device extending through said bore leading into said header tank and comprising a flange interposed between said coupling and said header tank, means carried by said flange providing a plurality of oil passages and a plurality of water passages extending adjacent to said oil passages, said water passages extending through said flange to establish communication between said bore and said header tank, and means interconnecting said oil passages with said lubricating system whereby the lubricant thereof is circulated through said oil passages.

3. An oil temperature regulating device for an internal combustion engine having a lubricating system and a cooling system comprising a radiator having a header tank with a port in a wall thereof, a tubular coupling secured to said tank with its bore leading thereinto through said port, and a conduit leading from said coupling to said engine, said regulating device comprising means providing a plurality of oil passages spaced to provide water passages therebetween, supporting means therefor engaging said coupling and retaining said passage-providing means in position with said water passages communicating with said conduit and said tank, and means connecting said oil passages into said lubricating system.

4. An oil temperature regulating device for an internal combustion engine having a lubricating system and a cooling system comprising a radiator having a header tank with a port in a wall thereof, a tubular coupling secured to said tank with its bore leading thereinto through said port, and a conduit leading from said coupling to said engine, said regulating device comprising means providing a plurality of oil passages spaced to provide water passages therebetween, said passage-providing means being supported by said coupling, with said water passages communicating with said conduit and said tank, and means connecting said oil passages into said lubricating system.

OSCAR C. PALMER.
